UNITED STATES PATENT OFFICE.

THOMAS A. BELL, OF TRENTON, NEW JERSEY.

MEASURING-MACHINE.

SPECIFICATION forming part of Letters Patent No. 267,826, dated November 21, 1882.

Application filed June 9, 1882. (No model.)

To all whom it may concern:

Be it known that I, THOMAS A. BELL, of Trenton, in the county of Mercer and State of New Jersey, have invented a new and Improved Measuring-Machine, of which the following is a full, clear, and exact description.

The object of my invention is to facilitate the measuring of belting, bands, or pieces of fabric.

10 The invention consists in the peculiar construction and arrangement of parts, as herein-after fully set forth, and pointed out in the claims.

15 Reference is to be had to the accompanying drawings, forming part of this specification, in which similar letters of reference indicate corresponding parts in all the figures.

Figure 1 is a longitudinal sectional elevation of my improved measuring-machine. Fig. 2 is an end elevation of the same. Fig. 3 is a longitudinal elevation of the wooden shell upon which the material or fabric is wound after having been measured. Fig. 4 is a longitudinal elevation of the tapered mandrel that is 25 passed into the shell.

The measuring-wheel A, which can have any suitable circumference—for instance, ten feet—has its circumference subdivided into feet and inches, and, if desired, into fractions of inches.

30 This wheel is journaled in the ends of supporting-bars B, pivoted to one of the standards C of the machine. A register-wheel, D, provided with a series of teeth, a, in its periphery, is pivoted to one of the bars B, and the teeth a are 35 marked 10, 20, or 30—that is, the successive multiples of the number of feet in the circumference of the wheel A. A stud or tooth, E, projecting sidewise from one of the spokes of the wheel, and being adapted to engage with

40 the teeth of the wheel D, rotates this wheel the distance of one tooth for every revolution of the wheel. A fixed pointer, F, is attached to one of the bars B, and points to the edge of the register-wheel D. The transverse shaft G 45 of the roll of material I is placed into hooks H at one end of the frame of the machine, and then the material is passed over a series of anti-friction rollers, e, and the end is passed around a wooden or other shell, J, made of two or

50 more parts, held together by a rubber sleeve, K, surrounding these two parts. A square

tapered mandrel, L, is passed through this shell, which is held on it by a spline, M, passed in between the shell and the mandrel. One end of this mandrel L is passed into a hook, N, at 55 that end of the machine-frame opposite the one to which the hooks H are fastened, and the other end of the mandrel is passed into the socket O' on the end of a journaled shaft, O, on which is mounted a cog-wheel, P, engaging 60 with a pinion, Q, on a shaft, Q', provided with the fixed and loose pulleys R R'. Each end of the machine-frame is provided with a transverse rod, S, on which two collars, T, provided with binding-screws T', are loosely mounted, 65 from which collars short spindles project, on which rollers V are loosely mounted, against which rollers the edges of the belt or fabric I rest, and which rollers guide the fabric and cause it to be wound evenly on the roll on the 70 shell J. These guide-rollers can be adjusted and locked any distance from each other, according to the width of the material.

The operation is as follows: The wheel D is so adjusted that the pointer F will be at 0, and the material to be measured is drawn under the wheel A and is passed around the shell J, which is pressed against the mandrel by the rubber sleeve K. By drawing part of the material under the wheel A this wheel is rotated more 75 or less. Power is then applied, and the entire belt or fabric is wound on the shell J, and as it passes under the wheel it rotates the same, which in turn rotates the register-wheel D. When all the material has passed under the 80 wheel A the length in multiples of the dimension of the circumference of the wheel A will be indicated by the pointer F on the wheel D, and the additional number of feet less than the circumference of the wheel A will be shown on 85 the circumference of this wheel. The mandrel L is then removed from the socket O' and the hook, and is withdrawn from the shell J, the two sections of which are pressed together by the rubber sleeve K, so that this shell can be 90 removed conveniently from the roll of the material.

Having thus fully described my invention, what I claim as new, and desire to secure by Letters Patent, is—

1. In a measuring-machine, the combination, with the frame C and the bolt-roll and receiv-

ing-shell, arranged at opposite sides of the frame, of the arms B, pivoted to the said frame, the measuring-wheel A, pivoted between the outer ends of the said arms and provided with the stud E, the toothed register-wheel D, pivoted to one of the said arms between its fulcrum and outer end, and the pointer F, rigidly attached to one of the said arms, substantially as and for the purpose set forth.

10 2. In a measuring-machine, the combination, with the measuring and registering wheels and devices for winding and unwinding the material to be measured, of the transverse rods S, the collars T, loosely mounted on the same, 15 the binding-screws T', and the guide-rollers V, mounted loosely on spindles attached to the collars T, substantially as herein shown and described, and for the purpose set forth.

3. In a measuring-machine, the combination, 20 with the measuring and registering wheels, of the shell J, formed of two or more parts, the rubber sleeve K, surrounding them, and the

mandrel L, which is passed through this shell, substantially as herein shown and described, and for the purpose set forth.

4. In a measuring-machine, the combination, with the measuring and registering wheels, of the shell J, the rubber sleeve K, surrounding it, the mandrel L, and the spline M, substantially as herein shown and described, and for the purpose set forth.

5. In a measuring-machine, the combination, with the measuring and registering wheels, of the shell J, the mandrel L, the hook N, the shaft O, provided with a socket, O', for receiving the end of the mandrel, and of devices for rotating the shaft, substantially as herein shown and described, and for the purpose set forth.

THOS. A. BELL.
